Patented Aug. 17, 1926.

UNITED STATES PATENT OFFICE.

ROBERT CLEMENS GALLETTI, OF MURS, BREGNIER-CORDON, FRANCE.

SYNTONIZATION OF CIRCUITS USED IN WIRELESS SIGNALING.

No Drawing. Application filed August 23, 1921, Serial No. 494,689, and in Italy August 5, 1920.

This invention relates to the syntonization of circuits used in wireless telegraphy.

Hitherto the practice has been to tune, or syntonize, firstly by endeavouring to obtain identity of periodicity by satisfying the equations $CL = C'L'$ wherein C C' and L L' are respectively the effective capacities and inductances of the circuits and secondly by manipulating the coupling

10 M $\sqrt{LL'}$

of each station so as to enhance the production of the free oscillations, without greatly impairing the efficiency of transformation.

The syntonization according to the present invention consists in producing a complete accord not only with regard to the frequencies of the inducing and induced currents, but also with regard to the shape of the curves of the waves and currents, a result which is obtained by manipulating the various electric constants or coefficients, including the radiation constant, until the algebraic equations hereinafter referred to are satisfied, for the purpose of attaining the following results:—pure sinusoidal elementary waves, impulsions of current, double pure sinusoidal characteristic roots, triple exponential real roots, transformer efficiency between aerial and condenser circuit coupled therewith, perfect accord between wave functions and transmitting current functions, exclusive propagation by earth, and perfect accord between both stations.

The algebraic equations to be satisfied according to the present invention are derived from the following general differential equation:—

$$40 \quad \frac{1}{C} \int_0^t \alpha dt + R\alpha + L \frac{d\alpha}{dt} + K \int_0^t \frac{d^3\alpha}{dt^3} = \text{const.}$$

This equation was proved in the article published by me in the Nuovo Cimento of October, 1917, under the title "Potenza di radiazione elettrica" and contains a new radiation coefficient K which like the other coefficients C , L , R and M is a concrete

factor in any wireless station. See also "Framework of Wireless Telegraphy" by 50 the applicant, printed by Cambridge University Press, published by Crossby Lockwood & Co.

In a given wireless station K cannot be freely manipulated, except by constructional changes of the aerial and earth, but in so far as it appears with the other coefficients in exact algebraic relations, it can be determined just as accurately as the other coefficients.

When designing a wireless plant it is essential approximately to determine beforehand the value of K from comparative constructional data, its exact value subsequently established for each erected station 65 being the controlling factor of the algebraic relations required to be satisfied according to the present invention.

In the above equation, the aerial current α is assumed to be a continuous function of time, a hypothesis which has to be rectified in the case of wireless transmission by considering the disturbance of the equilibrium after each interval of time $d t$ of continuous virtual action; that the actual current of 70 transmission is:

$$75 \quad \alpha + \frac{tK}{L} \frac{d^2\alpha}{dt^2}$$

and the actual wave reaction:

$$80 \quad \frac{tK^2}{L} \frac{d^4\alpha}{dt^4}$$

From this follows, inter alia, two facts of practical interest:

(1) Wherever the general integral of α contains a pure sinusoid, viz, without progressive damping, e. g.

$$85 \quad \frac{1}{e} \frac{t}{\sqrt{CL}}$$

such sinusoid is stopped (current together with all functions) in a given time, e. g.,

$$90 \quad T = \frac{CL^2}{K}$$

by mutual elimination of the main current α and of the sum of infinitesimal currents

$$5 \quad t \frac{K}{L} \frac{d^2\alpha}{dt^2}$$

together will all their functions.

(2) The wave transmitted is composed of infinitesimal elements, each of which is a continuous function such as:

$$10 \quad \gamma = \frac{K}{L} \frac{d^2\alpha}{dt^2} dt$$

(element of aerial current)

$$15 \quad K\ddot{\gamma} = \frac{K^2}{L} \frac{d^4\alpha}{dt^4} dt$$

(element of wave reaction).

The fact first above referred to is borne out experimentally in the electric single impulsive discharges, described in my article "Syntony of a quenched spark" published in the "Electrician" of 21st January, 1911, viz, electric discharges of very short duration, even below the half fundamental oscillatory period of the aerial, while the second fact is borne out by the propagation of waves, each element of which has a pure sinusoidal character, the effects being shared by the atmosphere and earth in the ratio of powers:

$$35 \quad \frac{K\dot{\gamma}^2}{2} - \frac{K\dot{\gamma}^2}{2} + K\gamma\ddot{\gamma}$$

for each element transmitted.

The facts referred to have also a bearing upon the possibility of wave reception in complete accord and consequently upon the efficiency and selectivity of reception, which surpass the results obtained solely with the reception by means of uniformity of preponderating period.

The invention may now be further elucidated by the following explanation so far as exclusive propagation by earth is concerned:

The intrinsic power of wave surface in real dielectric space is

$$50 \quad \frac{K\dot{\gamma}^2}{2}$$

(see page 15 of the "Framework of Wireless Telegraphy" referred to); consequently the difference between this power and the power that is emitted is the wave surface power in imaginary dielectric space, viz,

$$60 \quad K\gamma\ddot{\gamma} - \frac{K\dot{\gamma}^2}{2};$$

in other words, the latter is the imaginary continuation of the real dielectric wave through the centre of propagation.

In wireless transmission by means of an aerial having an earth connection, the latter is the centre and the imaginary dielectric wave becomes real earth propagation; indeed the earth being conductive, it stands for imaginary space with respect to the atmosphere, which is a dielectric.

The receiving aerial at a distance, which is crossed by the expanded shells of propagations transmitted, intersecting for a very small but constant fraction of volume ϵ^2 in it, is the seat of a total current

$$80 \quad \frac{\epsilon K}{L} t \frac{d^2\alpha}{dt^2}$$

(see pages 13 and 14 of the booklet referred to) provided that its characteristic equation be identical with the characteristic equation of the transmitting aerial.

Now, the atmosphere is not a perfect dielectric, just as the earth is not a perfect conductor, so that progressive absorption of the wave propagation takes place by either way. However, symmetrical absorption by both ways, air and earth, can only be fortuitous and occasional; consequently permanent reception in perfect accord for great distances of communication requires effective propagation by one way only, that is to say, in our case, the annihilation of the above-mentioned ratio or index of propagation distributed between air and earth:

$$100 \quad \frac{\dot{\gamma}^2}{2} - \frac{\gamma^2}{2} + \gamma\ddot{\gamma}$$

I have attained this by syntonizing in such a manner as to render

$$105 \quad \frac{\dot{\gamma}^2}{2}$$

negligible as compared with $\gamma\ddot{\gamma}$ with regard to the general integral of function for puffs of power emitted.

In view of the wave lengths adopted nowadays for long distance communications, one may say, broadly speaking, that reception in perfect accord beyond 1000 kms. requires single propagation by earth.

In practice it is also required for obtaining complete accord to reduce the emission to one time constant. I have attained this by syntonizing to satisfy a system of characteristic solutions, viz, by double sinusoidal roots or triple real exponential roots, in contradistinction to the approximate method hitherto used, viz, loosening of coupling and reduction of consuming reactions as compared with the oscillatory reactions of capacity and inductance.

It is further required to have a good transformation efficiency between the aerial and the condenser circuit coupled therewith and by using the method according to the present invention it so happens that the coupling required for most efficient transformation is the same coupling as that which goes with the double roots.

The invention is carried into effect by the usual practical means employed in wireless telegraphy, the conditions to be realized being expressed by algebraic relations of a definite character.

Thus, assuming the characteristic equations of the aerials of two communicating stations to be:

$$CKy^2 + CLy^2 + CRy + 1 = 0$$

$$C''K''y^2 + C''L''y^2 + C''R''y + 1 = 0$$

their identity is obtained by making

$$CK = C''K'' \quad CL = C''L'' \quad CR = C''R''$$

In these equations C, L, R and K are respectively the capacity, the self-inductance, the resistance and the radiation co-efficient of the aerial of the transmitting station and C'', L'', R'' and K'' respectively the capacity, the self-inductance, the resistance and the radiation coefficient of the aerial of the receiving station.

In order to obtain waves of a single periodicity, I simplify the wave functions by making use of double and triple characteristic roots expressed by the equations

$$f(r) = f'(r) = 0$$

and

$$f(s) = f''(s) = f'''(s) = 0$$

respectively.

In order to syntonize a simple aerial represented by the equation

$$\frac{1}{C} \int \alpha dt + R\alpha + \frac{Ld\alpha}{dt} + K \frac{d^2\alpha}{dt^2} = 0$$

I make use of the relations (see page 21 of the "Framework of Wireless Telegraphy" above referred to)

$$K = \frac{RCL}{9}$$

and

$$\frac{L}{CR^2} = \frac{1}{3}$$

from which results one triple real characteristic root

$$-\frac{L}{3K} = -\frac{3}{CR} = -\frac{R}{L} = -\frac{\sqrt{3}}{CL}$$

C, L, R and K being respectively the capacity, the self-inductance, the resistance and the radiation co-efficient of the aerial.

The syntonization of the aerial may also be effected by making use of the relation

$$K = \frac{RCL}{9}$$

either combined with the ratio

$$\sqrt{\frac{L}{CR^2}} < \frac{\pi}{2},$$

whereby a single impulsive discharge is obtained in the aerial and almost exclusively earth propagation or combined with the ratio

$$\sqrt{\frac{L}{CR^2}},$$

n times a multiple of π , whereby the emission of wave elements is obtained which have a pure sinusoidal function

$$\gamma = \sin \left(\frac{t}{\sqrt{CL}} + \varphi \right)$$

in a prolonged wave train up to the time

$$T = \frac{CL^2}{K} = \frac{L}{R}$$

of stopping and comprised in the arc

$$\sqrt{\frac{L}{CR^2}} = n\pi$$

The syntonization of an aerial and of a condenser circuit coupled therewith, the two being represented by

$$\frac{1}{C} \int idt + Ri + L \frac{di}{dt} + M \frac{d\alpha}{dt} = 0$$

$$M \frac{di}{dt} + \frac{1}{C} \int \alpha dt + R'\alpha + L' \frac{d\alpha}{dt} + K \frac{d^2\alpha}{dt^2} = 0$$

may be effected by the use of the combined relations

$$CL = C'L' \quad M^2 = KR \left(1 - \frac{C'R'}{CR} \right)$$

leading to the couple of characteristic roots (see page 24 of the "Framework of Wireless Telegraphy")

$$-\frac{R'}{2L'} \pm \sqrt{\left(\frac{R'}{2L'} \right)^2 - \frac{1}{CL}}$$

whereby an efficiency of one is obtained through the aerial, viz, identity of wave and primary reactions E. M. F., the current in the coupled circuit being also proportional to its E. M. F. induced by the aerial, while a group of other three roots has the property of causing the current in the aerial to be proportional to the E. M. F. induced therein by the circuit coupled therewith.

In the equation just referred to C, L, R, and K are the constants of the aerial circuit

as already indicated above and C' , L' , R' are respectively the capacity, the self-inductance and resistance of the condenser circuit coupled therewith, whilst M is the mutual inductance of the two circuits.

By using the combined relations

$$K = \frac{RCL'}{9}; \frac{L}{CR^2} = \frac{1}{3}$$

- 10 the coincidence of the group of three roots into one triple root

$$= -\frac{L'}{3K} = -\frac{3}{CR} = -\frac{R}{L} = -\frac{\sqrt{3}}{\sqrt{CL}}$$

- 15 is obtained.

On the other hand, if the relation $K = RCL'$ is used there results, amongst the roots of the group, the couple

$$20 \pm \frac{1}{\sqrt{-CL}}$$

whereby an efficiency of one, viz, identity of aerial and of ohmic reactions E. M. F. is obtained in the coupled circuit which receives in perfect accord.

By using as a first approximation the relations:

$$30 \frac{M^2}{LL'} = \frac{CR^2}{L} = \frac{K^2}{C'L'^3}; \frac{R'C'}{RC} = \frac{R'L}{RL'} = \theta$$

a small fraction of unity there results two couples of roots very close to

$$35 \pm \frac{1}{\sqrt{-CL}}$$

whereby an efficiency of one, viz, all wave energy consumed in primary, is obtained at the receiving wireless station which receives in perfect accord.

The use of the ratio

$$\frac{\sqrt{LL'}}{M} < \pi$$

45 produces a single impulsive discharge and the use of the ratio

$$\frac{\sqrt{LL'}}{M}$$

50 n times a multiple of π leads to the emission of prolonged trains of elementary sinusoidal functions, which are relatively pure.

By using as a second approximation the combined relations

$$\frac{M^2}{LL'} \frac{1}{1-\theta} = \frac{CR^2}{L} = \frac{K^2}{C'L'^3}$$

exclusive earth propagation is obtained, inasmuch as the ratio

$$65 \frac{\dot{\gamma}^2}{2} - \frac{\dot{\gamma}^2}{2} + \gamma\dot{\gamma}$$

becomes negligible for puffs of power emitted by two sinusoids, almost equal, in contrary sense, in period and in amplitude.

The use as a second approximation of the combined relations

$$\frac{M^2}{LL'} = \frac{CR^2}{L} (1+\theta) = \frac{K^2}{C'L'^3}$$

and as a third approximation:

$$75 \frac{M^2}{LL'} \frac{1}{1+\frac{CR^2}{L}\theta} = \frac{CR^2}{L} = \frac{K^2}{C'L'^3} \frac{1}{1+\theta\left(1+\frac{CR^2}{L}\right)^2}$$

80 produces a mixed propagation by air and by earth of wave elements having periodically single sinusoidal character, since the general integral of double pure imaginary roots $\pm h$ so obtained, has the form

$$85 A \sin (ht) + tB \sin (ht+\varphi)$$

The time constant h is actually equal to

$$90 \frac{1}{\sqrt{CL\left(1+\frac{\theta CR^2}{2L}\right)}}$$

95 As already hereinbefore stated, the invention can be applied with the ordinary apparatus and arrangement used in wireless telegraphy but its nature and manner of carrying it into effect differ entirely from the methods of syntonization hitherto known.

100 According to the known methods, syntonization was obtained by the continuous variation of one single electric coefficient which was considered to be sufficient for hitting upon one definite relation for one definite period, and the desired result could not be missed; very often a haphazard variation of all the electric coefficients which were in convenient reach, was effected more especially in view of the fact that useful results 105 were often attained although they could not be explained. It will however be seen that no haphazard variation of the various coefficients could possibly hit upon a definite regime governed by three algebraic relations 110 controlling in one definite combination amongst infinite possible ones at least three electric coefficients out of eight, viz:— K , M , C , L , R , C' , L' , R' , which are also limited for constructional and other practical reasons.

115 In order to obtain the regimes it is necessary to take into account, when manipulating each single electric coefficient, the simultaneous variations in the different algebraic relations defining the regime, so as to be able to follow the drift of the phenomena 120 towards the field of approximate regimes wherein it would be easy to find the final fine adjustment increasing the effects it is desired to obtain.

The various operations for obtaining in the first instance the regime fields which should be marked out on the apparatus employed at each station, are as follows:—

5 The general characteristic equation of 5th degree of a coupled aerial (see page 23 of the Framework of Wireless Telegraphy)

$$\frac{K^2}{C'L'^3} \left(\frac{K^2}{CLL'^2} + \frac{RK}{LL'} x + x^2 \right) - \frac{M^2}{LL'} x^4 + (x^2 + x^3) \left(\frac{K^2}{CLL'^2} + \frac{RK}{LL'} x + x^2 \right) = 0$$

from which it will be seen that the sole condition

$$\frac{M^2}{LL'} = \frac{K^2}{C'L'^3}$$

is sufficient for obtaining:—

$$\frac{K^2}{C'L'^3} \left\{ x^2(1-x)(1+x) + (1+x) \left(\frac{K^2}{CLL'^2} + \epsilon x \right) \right\} + x^2(1+x) \left(\frac{K^2}{CLL'^2} + \frac{RK}{LL'} x + x^2 \right) = 0$$

and

$$x^4 + \epsilon' x^3 + \left(\frac{K^2}{C'L'^3} + \frac{K^2}{CLL'^2} \right) x^2 + \epsilon \frac{K^2}{C'L'^3} x + \frac{K^2}{C'L'^3} \frac{K^2}{CLL'^2} = 0$$

15 wherein

$$\epsilon' = \frac{RK}{LL'} - \frac{K^2}{C'L'^3}$$

$$20 \quad \epsilon = \frac{RK}{LL'} - \frac{K^2}{CLL'^2} \quad \frac{1}{1+x}$$

Therefore what is required is only a rough approximation of the two regime conditions 25 $CL = C'L'$, $K = RCL'$ making ϵ and ϵ' rather small with respect to unity, together with the single definite relation

$$30 \quad \frac{M^2}{LL'} = \frac{K^2}{C'L'^3}$$

in order to obtain the roots:—

$$35 \quad p_1, p_2 = \frac{L'}{K} x, \frac{L'}{K} x_2 = -\sqrt{-\frac{1}{C'L'}}$$

$$p_1, p_2 = \frac{L'}{K} x_3, \frac{L'}{K} x_4 = -\frac{L' \epsilon'}{K^2} \pm \sqrt{\frac{L'^2 \epsilon'^2}{R^2 4} - \frac{1}{CL}}$$

so that one wave disappears impulsively in time

$$40 \quad \tau = \frac{L'C'L'}{K}$$

(see page 13 of "The Framework of Wireless Telegraphy") or in arc

$$45 \quad \sqrt{\frac{C'L'^3}{K^2}} = \sqrt{\frac{LL'}{M^2}}$$

of its own sinusoid, the other wave following in about the same time provided ϵ' be positive. The latter can be seen from its expression above referred to whilst

$$50 \quad \sqrt{\frac{LL'}{M^2}} < 2\pi$$

is only natural.

can be transformed by the substitution of

$$x = \frac{K}{L'} p$$

10

and be grouped (assuming R' to be negligible which is quite accurate in practice) into the form:—

$$\frac{M^2}{LL'} \left(\frac{K^2}{CLL'^2} + \frac{RK}{LL'} x + x^2 \right) = 0$$

At the station provided with any sort of quenched spark and having the usual constructional proportions the wireless operator cannot miss the desired result up to this point since a continuous manipulation even of one electric coefficient only, must hit upon the single definite equivalence

$$60 \quad \frac{M^2}{LL'} = \frac{K^2}{C'L'^3}$$

65

of two expressions having the same constructional limits, zero and one (see page 35 of "The Framework of Wireless Telegraphy"). At this point the impulsive whistle comes into play, its pitch being determined by the time being required to charge the primary capacity to the discharge voltage of the spark and by regulation of the resistance in the supply mains it can conveniently be arranged that it shall have a frequency of 5,000 to 10,000 sparks per second. Now, the wireless operator must look for that particular spot in the field of the whistle that will give the clearest pitch, this corresponding to the exact adjustment of $CL = C'L'$ together with

$$70 \quad \frac{M^2}{LL'} = \frac{K^2}{C'L'^3}$$

75

or $M^2 CL' = K^2$ since the periods thereby almost coincide and the action that takes place is almost according to the general integral of regime (1), (2), (3) (see page 27 of "The Framework of Wireless Telegraphy").

Having obtained a good clear whistle as a guidance and the exact equivalence of $M^2 CL' = K^2$ the wireless operator should now try to push the coupling towards one, manipulating C' and L but being careful not to touch either of the coefficients M , C , L' except with due mutual compensation, that is to say if he wishes to double M , he should halve L' and C simultaneously. In

80

85

90

95

this manner he will hit upon a field of whistle wherein he will notice a sudden fall of the pitch though still quite clear, which means that the third condition of regime 5 namely $M^2 = KR$ has been obtained because the very substantial increase in efficiency of an exact regime having

$$10 \quad \frac{M^2}{LL'}$$

nearly equal 1 (see page 23 of "The Framework of Wireless Telegraphy") discharges the primary circuit of its single charge energies much more completely and thus more 15 time is required for re-charging the primary from the mains (see page 31 of "The Framework of Wireless Telegraphy").

When searching for the regimes and in order to differentiate between one regime 20 field and another, besides the guidance by the lowest clear pitch of whistle, it is necessary to keep an eye on the ratio of the ampere meter readings in the primary circuit and in the aerial; at a good point of the 25 regime the aerial current will be seen to increase with a kick while the primary decreases. Such comparisons of current readings are sufficient for the guidance to a final 30 adjustment when it is decided to increase the power and to render the whistle too high for audibility by removing the resistance in the supply mains.

It is possible that the aerial without being actually defective does not conveniently 35 allow the expression

$$\frac{K^2}{C'L'^3}$$

40 to approach unity as much as might be desired for reasons of efficiency, or again, it may be required to increase considerably the primary capacity C with a view to allowing greater power with a given voltage. In such cases the wireless operator should pass from 45 his last marked field of approximate regimes viz:—the conditions

$$\frac{M^2}{LL'} = \frac{K^2}{C'L'^3}, \quad M^2CL' = K^2$$

50 to those of the triple real root

$$-\frac{L'}{3K} = -\frac{3}{CR} = -\frac{R}{L} = -\frac{\sqrt{3}}{\sqrt{CL}}$$

55 and of sinusoidal roots

$$-\frac{R'}{2L'} \pm \sqrt{\left(\frac{R'}{2L'}\right)^2 - \frac{1}{CL}}$$

for which (see pages 23, 24, 21 of "The 60 Framework of Wireless Telegraphy").

$$\frac{K^2}{C'L'^3} = \frac{1}{2} \frac{M^2}{LL'} = \frac{1}{3} M^2CL' = 9K^2$$

$$M^2 = KRCL = C'L'$$

The required operations are first to triple 65 C and L' simultaneously and then to push up again the coupling to

$$\frac{M}{\sqrt{LL'}} = \frac{1}{\sqrt{3}}$$

70

whilst keeping $M^2CL' = 9K^2$ constant.

The reception regimes are guided on a transmitted regime with the advantage that the values of coupling between transmission 75 and reception are independent (see pages 32, 33 of "The Framework of Wireless Telegraphy"). A reception of regime can also be guided on any continuous wave transmission by following a fairly wide interference 80 field which makes itself heard round about a definite regime point which is itself silent, or reduced to a gurgle when the detecting apparatus is in the form of a crystal. That is to say no attempt should be made to improve the acoustic properties of the interference note as heard through the intermediary of the crystal but the line of lower pitch should be followed until the interference note disappears in a greatly reduced region 90 when the employment of other detecting means such as thermic apparatus, heterodyne, Goldschmidt wheel, etc., will reveal an immensely increased received current. Here again the fundamental regime is $M^2CL' = K^2$ 95 while the manipulation of C' and L is free when passing from one wave length to another. The manipulation of C' may be effected by a condenser to earth.

Having now described my invention, 100 what I claim as new and desire to secure by Letters Patent is:—

1. The method of syntonization between two wireless stations whose sending and receiving aerials have a radiation constant K 105 which comprises causing a wave to be propagated in the sending aerial, regulating the capacity C , resistance R , inductance L of each aerial so as to satisfy at all times the following relationship 110

$$\frac{1}{C} \int_0^t dt + R\alpha LK \int_0^t \frac{d^3\alpha}{dt^3} dt = \text{constant}$$

where α is the aerial current at any given 115 instant of time.

2. The method of syntonization as claimed in claim 1, the additional step of regulating the capacity C , the resistance R and the inductance L of the aerial of the sending station and the capacity C'' , inductance L'' , and resistance R'' of the receiving aerial so that the following relations occur: 120

$$CK = C''K''; \quad CL = C''L''; \quad CR = C''R''$$

3. The method of syntonization which 125 comprises varying the aerial current caused to flow in an aerial of radiation constant K

whose inductance is L to produce an aerial current α at time t such that γ which is the aerial current of a continuous element of the wave of current variation be defined by

$$5 \quad \gamma = \frac{K}{L} \frac{d^2\alpha}{dt^2} dt$$

and $\ddot{\gamma}$ element of the wave reaction of the 10 propagated wave be defined by the relationship

$$K\ddot{\gamma} = \frac{K^2}{L} \frac{d^4\alpha}{dt^4} dt$$

15 such that

$$\frac{\gamma^2}{2} - \frac{\ddot{\gamma}^2}{2} + \gamma\ddot{\gamma}$$

20 is negligible, i. e., such that $\frac{\gamma^2}{2}$ is negligible compared with $\ddot{\gamma}^2$ and thus to obtain exclusive earth propagation of the radiated 25 wave.

25 4. In the method defined in claim 1 the additional step of regulating the said capacities, resistances and inductances so that they have the following relationship,

$$30 \quad -\frac{L}{3K} = -\frac{3}{CR} = -\frac{R}{L} = -\frac{\sqrt{3}}{\sqrt{CL}}$$

35 5. The method of syntonization of a wireless station comprising an aerial with a radiation constant K and a capacity C , resistance R and inductance L and a coupled condenser circuit of capacity C' , resistance R' , inductance L' and where M is the mutual inductance of the aerial and condenser circuits, comprising regulating the above inductances, capacities, and resistances, and causing the passage of a current i at a time 40 t to flow in the condenser circuit and the current α at time t to flow in the aerial circuit so that the following relations are obtained:

$$50 \quad \frac{1}{C} \int idt + Ri + L \frac{di}{dt} + M \frac{di}{dt} = 0$$

and

$$55 \quad M \frac{d\alpha}{dt} + \frac{1}{C'} \int \alpha dt + R\alpha + L' \frac{d\alpha}{dt} + K \frac{d^2\alpha}{dt^2} = 0$$

55 and also regulating the said capacities, inductances and resistances so as to obtain the following relationships:

$$60 \quad CL = C'L'$$

and

$$65 \quad M^2 = KR \left(1 - \frac{C'R'}{CR} \right)$$

6. In the method defined in claim 5, additionally regulating the resistances and capacities and inductances of the aerial and inductance of the coupled condenser circuit to obtain the following relationships:

$$70 \quad K = \frac{RCL'}{9}$$

$$75 \quad \frac{L}{CR^2} = \frac{1}{3}$$

and also the following relationships:

$$80 \quad -\frac{L'}{3K} = -\frac{3}{CR} = -\frac{R}{L} = -\frac{\sqrt{3}}{\sqrt{CL}}$$

7. The method of syntonization of a wireless station comprising an aerial with a radiation constant K and a capacity C , resistance R and inductance L and a coupled condenser circuit of capacity C' , resistance R' , inductance L' and where M is the mutual inductance of the aerial and condenser circuits comprising regulating the above inductances, capacities, and resistances, and causing the passage of a current i at a time t to flow in the condenser circuit and the current α at time t to flow in the aerial circuit so that the following relations are obtained:

$$90 \quad \frac{1}{C} \int idt + Ri + L \frac{di}{dt} + M \frac{di}{dt} = 0$$

$$95 \quad M \frac{d\alpha}{dt} + \frac{1}{C'} \int \alpha dt + R'\alpha + L' \frac{d\alpha}{dt} + K \frac{d^2\alpha}{dt^2} = 0$$

100 and also regulating the said capacities, inductances and resistances so as to obtain the following relationships:

$$105 \quad CL = C'L'$$

and

$$110 \quad M^2 = KR \left(1 - \frac{C'R'}{CR} \right)$$

and

$$115 \quad \frac{M^2}{LL'} = \frac{CR^2}{L} = \frac{K^2}{C'L'^2}; \quad \frac{R'C'}{RC} = \frac{R'L'}{RL'} = \theta$$

where θ is a small fraction of unity.

8. The method of syntonization of a wireless station comprising an aerial with a radiation constant K and a capacity C , resistance R and inductance L and a coupled condenser circuit of capacity C' , resistance R' , inductance L' and where M is the mutual inductance of the aerial and condenser circuits comprising regulating the above inductances, capacities, and resistances, and causing the passage of a current i at a time

t to flow in the condenser circuit and the current α at time *t* to flow in the aerial circuit so that the following relations are obtained:

$$5 \quad \frac{1}{C} \int idt + Ri + L \frac{di}{dt} + M \frac{di}{dt} = 0$$

$$M \frac{d\alpha}{dt} + \frac{1}{C'} \int \alpha dt + R' \alpha + L' \frac{d\alpha}{dt} + K \frac{d^2\alpha}{dt^2} = 0$$

10 and also regulating the said capacities, inductances and resistances so as to obtain the following relationships:

$$CL = C'L'$$

15 and

$$M^2 = KR \left(1 - \frac{C'R'}{CR} \right)$$

and

$$20 \quad \frac{M^2}{LL'} = \frac{CR^2}{L} = \frac{K^2}{C'L'^3}; \quad \frac{R'C'}{RC} = \frac{R'L}{RL'} = \theta$$

where θ is a small fraction of unity, and

$$\frac{\sqrt{LL'}}{M} < \pi.$$

25

9. The method of syntonization of a wireless station comprising an aerial with a radiation constant K and a capacity C , resistance R and inductance L and a coupled condenser circuit of capacity C' , resistance R' , inductance L' and where M is the mutual inductance of the aerial and condenser circuits comprising regulating the above inductances, capacities, and resistances, and causing the passage of a current i at a time *t* to flow in the condenser circuit and the current α at time *t* to flow in the aerial cir-

cuit so that the following relations are obtained:

$$40 \quad \frac{1}{C} \int idt + Ri + L \frac{di}{dt} + M \frac{di}{dt} = 0$$

$$45 \quad M \frac{d\alpha}{dt} + \frac{1}{C'} \int \alpha dt + R' \alpha + L' \frac{d\alpha}{dt} + K \frac{d^2\alpha}{dt^2} = 0$$

and also regulating the said capacities, inductances and resistances so as to obtain the following relationships:

$$50 \quad CL = C'L' \text{ and } M^2 = KR \left(1 - \frac{C'R'}{CR} \right)$$

$$\frac{M^2}{LL'} = \frac{CR^2}{L} = \frac{K^2}{C'L'^3}; \quad \frac{R'C'}{RC} = \frac{R'L}{RL'} = \theta$$

where θ is a small fraction of unity,

$$\frac{\sqrt{LL'}}{M} < \pi$$

and

$$60 \quad \frac{M^2}{LL'} \frac{1}{1-\theta} = \frac{CR^2}{L} = \frac{K^2}{C'L'^3}.$$

10. In the method defined in claim 9, additionally regulating the above mentioned electrical constants so as to obtain the following relationships:

$$65 \quad \frac{1}{LL'} \frac{1}{1+\theta} = \frac{CR^2}{L} = \frac{K^2}{C'L'^3} \frac{1}{1+\theta \left(1 + \frac{CR^2}{L} \right)}$$

70 where θ is a small fraction of unity.

In testimony whereof I have signed my name to this specification.

ROBERT CLEMENS GALLETTI.
